UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,253,235.

Specification of Letters Patent. Patented Jan. 15, 1918.

Application filed June 8, 1916. Serial No. 102,499.

To all whom it may concern:

Be it known that I, ARTHUR J. HALL, a subject of the King of Great Britain, and a resident of Wilkinsburg, in the county of 5 Allegheny and State of Pennsylvania, have invented a new and useful Improvement in Control Apparatus, of which the following is a specification.

My invention relates to control apparatus 10 and particularly to liquid rheostats.

The object of my invention is to provide a plurality of electrodes having very small initial contact areas that are relatively widely separated and large final contact 15 areas that are disposed in relatively close proximity.

In liquid rheostats that have heretofore been proposed, the entire lower edges of the electrodes establish initial contact with the 20 electrolyte and, since the electrodes are of the same size and are assembled in side-by-side relation, the final areas of contact with the electrolyte are separated the same distance as the points of initial contact. Since 25 the resistance to the flow of an electric current through a liquid rheostat is inversely proportional to the submerged area of the electrodes and directly proportional to the distance between the points of contact of 30 adjacent electrodes, it is desirable to have the initial contact points of small areas and widely separated and to have the final contact surfaces near together and of large areas in order to secure a rheostat of relatively 35 large range.

My invention embodies a plurality of tapered electrodes having contact tips disposed at varying distances from the ends of the respective electrodes so that the points 40 of initial contact of adjacent electrodes will be more widely separated than the distance between the electrodes.

Figure 1 of the accompanying drawing is a top plan view of a liquid rheostat embodying my invention, and Fig. 2 is a side view, partially in section and partially in elevation, of the rheostat shown in Fig. 1.

The rheostat shown in the drawing comprises a main electrode-containing tank 1, 50 an auxiliary electrolyte-supply tank 2, a valve 3 for controlling the level of the electrolyte in the tank 1, a pump 4 for supplying electrolyte from the tank 2 to the tank 1 and a plurality of electrodes 5 that are 55 disposed in side-by-side relation within the

tank 1. The valve 3 is movably mounted within an outlet port 16 and is adapted to be actuated by a rod 6 that is controlled by a suitable operating mechanism (not shown). The lower cylindrical portion of 60 the valve 3 closes the opening 16 and the electrolyte, which is supplied to the tank 1 from the tank 2 by the pump 4, flows over the top and through the hollow valve 3 to the tank 2. The level of the electrolyte 65 therefore corresponds to the position of the valve 3. Alternate electrodes are respectively connected to terminal members 10 and 11 by conducting bars 12 and 13. Each of the electrodes 5 comprises a rectangular top 70 portion 7, a tapered portion 8 and a tip 9. The tapered portions of the various electrodes terminate in points at varying distances from the ends of the electrodes and the tips 9 are secured to such points, thus 75 arranging the tips 9 in staggered relation or substantially diagonal alignment across the group of electrodes.

With the electrolyte-controlling valve 3 in the position shown in the drawing, the 80 liquid will rise in the tank to a level corresponding to the top of the valve 3, which is indicated by the dotted line 14, and, as the valve is raised through its various positions, the level of the electrolyte will be correspondingly raised until, for the final position, it will immerse the portions of the electrodes below the line 15. When the valve 3 is in the position shown, the points of contact of the electrode with the liquid will be 85 separated by the distance d , as shown in Fig. 1, whereas, when the liquid has risen to its final height, the entire contact surface of the electrodes 5 will be immersed and the distance between contact surfaces will then 90 be the distance d' . It will be noticed also that the portions of the electrodes that are initially immersed are very small and that the surfaces of the electrodes that are finally immersed are relatively great, thereby providing a rheostat of considerable range. 95

The form and dimensions of the electrodes may obviously be changed in many respects without departing from the spirit and scope of my invention. It is to be understood, therefore, that my invention comprises all modifications which fall within the scope of the appended claims. 105

I claim as my invention:

1. In a liquid rheostat, the combination 110

- with a tank, of a plurality of stationary tapered electrodes disposed in side-by-side relation in the tank, said electrodes having independent tips that are positioned in a diagonal line across said group of electrodes.
5. In a liquid rheostat, the combination with a tank, of a plurality of stationary electrodes disposed in side-by-side relation within said tank, and independent tips for said electrodes that are positioned in staggered relation.
10. In a liquid rheostat, the combination with a tank, of a plurality of electrodes disposed in side-by-side relation, said electrodes being tapered and terminating in conducting tips that are diagonally positioned across a portion of said group of electrodes.
15. In a liquid rheostat, the combination with a tank, of a plurality of electrodes disposed in side-by-side relation within said tank, each of said electrodes being tapered and terminating in a conducting tip that is at a distance greater than the distance between electrodes from the adjacent electrode tip.
20. In a liquid rheostat, the combination with a tank, of a plurality of tapered electrodes each terminating in a point, and a tip
25. secured to the point of each electrode, said tips being separated a greater distance than the space between said electrodes.
6. In a liquid rheostat, the combination with a tank adapted to contain an electrolyte and means for varying the level of the electrolyte in said tank, of a plurality of electrodes disposed in side-by-side relation and having bottom portions so positioned that the points of contact of the electrodes with the electrolyte are relatively widely separated for one level of electrolyte and are relatively close together for another level of electrolyte.
30. 7. In a liquid rheostat, the combination with a tank adapted to contain an electrolyte, and means for varying the height of the electrolyte in said tank, of a plurality of electrodes rigidly positioned within said tank in side-by-side relation, said electrodes being tapered and terminating in a tip, said tips being more widely separated than the distance between said electrodes.
35. 40. 45. In testimony whereof, I have hereunto subscribed my name this 31st day of May, 1916.

ARTHUR J. HALL
